(57) **CLAIM**

The ornamental design for a "printer with an automatic document feeder input tray," as shown and described.

DESCRIPTION

FIG. 1 is a top, front, right side perspective view of an example printer with an automatic document feeder input tray;

FIG. 2 is a front view of the example printer of FIG. 1;

FIG. 3 is a right side view of the example printer of FIG. 1;

FIG. 4 is a top view of the example printer of FIG. 1;

FIG. 5 is a left side view of the example printer of FIG. 1; and,

FIG. 6 is a back view of the example printer of FIG. 1.

The broken lines are shown for the purpose of depicting portions of the article and form no part of the claimed design.

1 Claim, 6 Drawing Sheets
